[57]

CLAIM

The ornamental design for a contoured arm seat, as shown and described.

DESCRIPTION

FIG. 1 is a perspective view of the contoured arm seat showing my new design;

FIG. 2 is a right side elevational view, the left side being a mere image thereof;

FIG. 3 is a front elevational view thereof;

FIG. 4 is a rear elevational view thereof;

FIG. 5 is a perspective view of a second embodiment of a contoured arm seat showing my new design in the form of a loveseat;

FIG. 6 is a left side elevational view of FIG. 5, the right side being a mere image thereof;

FIG. 7 is a front elevational view of FIG. 5;

FIG. 8 is a rear elevational view of FIG. 5;

FIG. 9 is a perspective view of a third embodiment of a contoured arm seat showing my new design in the form of a chair;

FIG. 10 is a left side elevational view of FIG. 9, the right side being a mere image thereof;

FIG. 11 is a front elevational view of FIG. 9; and,

FIG. 12 is a rear elevational view of FIG. 9.

CERTIFICATE OF CORRECTION

PATENT NO. : Des. 405,287

Page 1 of 5

DATED : February 9, 1999

INVENTOR(S) : Ronald N. Watson

It is certified that error appears in the above-identified patent and that said Letters Patent is hereby corrected as shown below:

In the drawings, cancel Sheets 1 to 3, Figures 1 to 12, and replace the canceled sheets with new Sheets 1 to 3, Figures 1 to 12, attached hereto.

Title page, should be deleted and replaced with the attached Title page, showing the illustrative figure.

Signed and Sealed this

Twenty-eighth Day of December, 1999

Attest:

Q. TODD DICKINSON

Attesting Officer

Acting Commissioner of Patents and Trademarks
